UNITED STATES PATENT OFFICE.

JOHN ARTHUR KEESEY, OF BROOKLYN, NEW YORK, AND ALFRED SHEDLOCK, OF CANNONDALE, CONNECTICUT; SAID SHEDLOCK ASSIGNOR TO SAID KEESEY.

SIGNALING APPARATUS.

1,301,271.

Specification of Letters Patent. Patented Apr. 22, 1919.

Application filed September 28, 1917. Serial No. 193,631.

To all whom it may concern:

Be it known that we, JOHN ARTHUR KEESEY and ALFRED SHEDLOCK, citizens of the United States, residing, respectively, at 5 Brooklyn, county of Kings, State of New York, and Cannondale, Fairfield county, State of Connecticut, have jointly invented new and useful Improvements in Signaling Apparatus, of which the following is a 10 specification.

The central or main communicating stations of mechanical telegraph systems are often equipped with two or more machines, adapted to coact with individual message 15 receiving and sending machines located at different distant stations.

This invention has for its object to combine in a single apparatus, for use at the main communicating station, a plurality of 20 message sending and message receiving devices and their accompanying operating appurtenances. Another object is to cause aural signals to be sounded on a single gong, that is common to all of the message receiving devices of the apparatus, when each 25 of the said message receiving devices is actuated, without interfering with the mechanism of the other devices. A further object is to provide simple means for adjusting 30 and taking up slack occurring in the connections of coacting apparatus to insure positiveness of action between them and to enable the indicating pointers of coacting apparatus to be set to work or move in unison. 35

These features with other improvements in the construction of this class of apparatus are illustrated in the accompanying drawings to which we will now refer.

Figure 1, is a face view of one end of the 40 apparatus showing a message indicating dial, the operating handles and the pointers.

Fig. 2, a similar view of the other end of the apparatus.

Fig. 3, a longitudinal vertical section, 45 taken on the line 3, 3, Fig. 1.

Fig. 4, a transverse section on the line 4, 4, Fig. 3.

Fig. 5, a sectional view of one of the operating handles, at right angles to the view 50 Fig. 3.

Fig. 6, a detached view of one of the pointers, showing the method of its adjustment, and:

Fig. 7, a vertical section of an apparatus 55 adapted for use at a subsidiary station to

operate in conjunction with one of the message sending and one of the return message receiving devices of the main communicating apparatus, and:

Fig. 8, a plan view of one half of the 60 main apparatus, showing the principal operating devices in full and with the upper half of the cylindrical casing removed.

The inclosing case of the apparatus is cylindrical, formed in halves 9, and 10, see 65 Fig. 4 of the drawing, longitudinally divided and secured together by screws 11, which pass through one of the parts into flanges formed inside the edges of the other part. Bearings, &c., for the various mechanisms are provided in centrally divided web frames, inside of and preferably integral with the two halves of the cylindrical casing. One of the web frames 12, is located at the central part and others 13, near each 70 end of the casing. The bearings for the central shafts 14, which carry all of the message sending and receiving wheels and for the hammer shafts 15, 15, which are located at the sides of the wheels, are in the 75 horizontal divisions of the web frames. The bearing shafts 16, 16, of the guide pulleys for the chains and all other operating parts of the apparatus are carried by the lower half of the cylindrical body. This construction provides for ready removal of the upper part of the casing, facilitating assembling of the operating parts, &c., and leaving all of the devices fully exposed in 80 operative condition, for inspection adjustment, &c., thereof. The two halves 9 and 10, of the casing may, for convenience of manufacture, be made in sections joined, as by socket connections 17, and held together 85 by screws or rivets passed through said connections.

Message indicating dials 18, 19, are divided at their horizon-diameters, the halves of each of them being secured respectively to the end frames 13, of the upper and lower 90 halves of the casing.

The multi-message or order sending and receiving apparatus shown is adapted for communication between a central and four distinct distant stations. It is, by the markings on the dials illustrated, intended for use on a ship, to be located on the bridge or other officer's station to communicate with the engineers' departments of the starboard and port engines, as shown at Fig. 1, and 105 110

with the bow and stern docking crews, as shown at Fig. 2.

There are four chain wheels, two for sending and two for receiving messages, located between the central web frame 12, and each of the end web frames 13. These two sets of wheels and their appurtenances are in all essential respects similar, so a description one set applies to both, like parts being similarly designated.

The inner ends of the shafts 14, seat in a bearing 20, of the central web frame 12, and their outer ends extend through the central bores of the end web frames 13. Each shaft carries or is integral with a chain wheel 21, which carries a chain 22; adjacent this wheel is a wheel 23, on which is a chain 24; the next wheel 25, carries a chain 26, and on the outer wheel 27, is a chain 28.

On the outer end of one of the shafts 14, is adjustably secured an operating handle 29, provided with a pointer 30; a handle 31, provided with a pointer 32, is connected to the chain wheel 23, being adjustably secured to its sleeve 33, which is fitted to rotate on the shaft 14. These adjusting means provide for setting the pointers 30 and 32, to agree with the indicating pointers of a co-acting apparatus located at a distant station, as hereafter described, and may consist of disks 34 and 35, and tightening nuts 36 and 37, on the shaft 14, and sleeve 33, respectively, the hubs of the handles being between the disks and nuts. The disks are keyed or otherwise secured to the shaft and sleeve and the contacting faces of the disks and hubs of the handles are provided with engaging teeth or radially serrated to insure rigid connections between the handles and their respective chain wheels.

The chain wheel 25, is on a sleeve which rotates on the sleeve 33, and the wheel 27, has a sleeve rotatable on the sleeve of wheel 25, and is fitted to rotate in the central bore of the web frame 13. On the outer ends of the sleeves of the wheels 25 and 27 are attached pointers 38 and 39, and located in front of the indicating dial 18, they are adapted to be adjusted and suitably set. These adjusting means are shown as segmental disks 40, 41, having peripheral flanges and are firmly secured to the outer ends of the sleeves of the wheels 35 and 37, the pointers being formed to seat on the flanged peripheries of the segmental disks and held thereon by screws, as shown in Figs. 1 and 6.

The operating handles 42, 43, with their pointers 44, 45, of the docking indicating end of the apparatus, see Fig. 2, are, when in normal position, preferably diametrically arranged and are adjustably connected to their respective chain wheels in manner similar to the connections of the handles 29, 31, and the return signal pointers 46, 47,

at this end of the apparatus are carried on segmental disks 40, 41, connected to their respective chain wheels, in manner before described.

The message receiving wheels have projecting from their sides pins or teeth 48, see Fig. 8, preferably equal in number to the divisions of the indications on the dials. These teeth work against the double acting pawls 49, 49, carried on short arms 50, 50, which are secured to the shafts 15, 15, see Fig. 8, the pawls of one of the shafts being acted upon or about to be acted upon by the teeth while the pawls of the other shaft will be in spaces between the teeth, as shown, whereby, when any of the return signal wheels are moved both shafts will be rocked for each full movement of a tooth and as the pointer of the actuating wheel is, in accordance with the pointer of the sending signal apparatus, moving from one indicating division to another. The gong 51, is thus struck by the two hammers 52, 53, which are carried by the shafts 15, 15, through the medium of the reaction springs 54, applied to hammers or to the shafts in the usual manner. The gong 51, is secured to the central web frame.

When it is required to send different orders to the crews of the engines of twin propellers the handles 29, 31, will be separately manipulated, but to facilitate sending the same orders to both of the crews provisions are made for locking the two handles together, so that the two receiving apparatus will be simultaneously set. A simple arrangement for this purpose consists in making one of the handles, as handle 31, see Fig. 5, slideable on its lever and providing engaging lugs 55, see Fig. 3, adapted, when handle 31, is depressed, to lock the two handles together. To retain the handle 31, on its lever and to limit its movement thereon a screw 56, passes through the side of the handle into a notch formed in the side of the lever, and a toothed spring 57, attached to the other side of the lever engages the lower end of the handle 31, and holds it clear of the handle 29. The handle 31, is held in depressed position by the tooth of the spring catching into a notch formed in the inside of the handle, see Fig. 5, thus holding the two handles locked together.

The two runs of the chains 22, 24, 26, and 28, extend down through the bottom of the cylindrical casing after passing over guide pulleys 58, which are fitted to freely rotate on the shafts 16, 16. These shafts are held in the web frames 12, 13.

59, designates the upper end of a pedestal or standard to which the apparatus may be connected by screws or bolts 60, applied to flanges at the upper end of the pedestal, curved to properly hold the cylindrical body.

5 Stops 61, are provided for limiting the movements of the operating handles within their proper range of action. These stops may be cast or formed with the cylindrical casing as lugs projecting from the end edges.

10 To insure correct transmission of messages and orders between the main and substations, and so avoid mistakes, it is essential that the connected apparatus be at all times in proper working condition and work uniformly together; therefore means are provided for readily correcting imperfections occurring in the operating and indicating devices. Such means are shown in an apparatus suitable for use at substations, see Fig. 7, adapted to coact with the adjusting devices of the main station apparatus, before described. This Fig. 7, is a vertical section giving the operating parts in detail sufficiently clear to enable a proper understanding of the coacting operations of the two apparatus; it being understood that the chains of the coöperating devices of the two apparatus will be suitably connected by rods, &c. The dial 62, is attached to the front plate 63, which is adequately connected to the rear plate 64. A shaft 65, has a bearing in the rear plate and extends through a central bore in the front plate. This shaft carries a pulley or wheel 66, to which end of the chain 67, is fastened, and adjacent this wheel is a wheel 68, similarly holding a chain 69. The chains 67, and 69, pass around their respective wheels in opposite directions. 35 Wheel 68, is connected to or forms part of a sleeve 70, rotatably seated on the shaft 65. A handle 71, loosely fitted on the shaft is clamped between disks 72, 73, keyed on the shaft and the sleeve respectively, by a nut 74, 40 on the end of the shaft, when the disks and their connected wheels have been turned to tighten the chains 67, 69, and all their connections; the handle having been set with its pointer 75, at a mark on the dial corresponding to the mark on the dial of the main apparatus at which the return signal pointer of the connected device is set. This pointer which may be the one designated 38, 45 is also adjustable relative to its operating chain 26; this double adjustment greatly facilitates setting the two apparatus to work in unison. On the sleeve 70 is the sleeve of the wheel 76, carrying a chain 77, and adjacent this wheel is a wheel 78, to which is attached a chain 79, and which is on a sleeve having a bearing in the front plate 63. The chain 77 passes from one side of the wheel 76, and the chain 79 passes from the opposite side of the wheel 78. The wheels 76 and 78 50 are connected together by adjustable means and then act as a single chain wheel or pulley. Disks 80, 81, are keyed to the ends of the sleeves of the wheels 76, 78, and between them is the hub of a pointer 82, which, by 55 nut 83, fitted on the end of the sleeve 76, is

clamped between the two disks. The chains 77, and 79, act as a single chain and constitute a part of a complete connection by being connected to the chain 22, of the main apparatus, whose operating handle 29, is set 70 to accord with the pointer 82, when the slack in this part of the system has been taken up by manipulating the disks 80, 81.

10 The other message sending wheels and receiving wheels of the main apparatus are 75 similarly connected in pairs with apparatus located at other substations.

84, designates a disk gong, 85, a hammer carried on a rock shaft 86, which, by an attached escapement, is actuated by teeth 87, 80 projecting from the side of one of the wheels of the message receiving device. The message indications on the dial 62, are similar to and correspond with the message markings on the dial of the main apparatus 85 indicated by the pointers of the connected operating devices.

15 The cylindrical casing is fully inclosed and the operating parts of the apparatus protected by glass covers 88, applied to the 90 ends of the casing. These glass covers are shown held in flanged rims 89, which fit inside the end edges of the casing and are held therein by screws. When the upper half of the casing is to be removed the screws connecting it to the rims 89, are taken out. The glass plates with their rims may be centrally divided, in manner similar to the division of the dials, each of the halves thereof being left secured to the upper and lower halves respectively of the casing when the upper half of the casing is removed. 100

20 We claim:

1. A central station signaling apparatus, comprising a plurality of message sending 105 wheels and an equal number of message receiving wheels all on a common axis, adapted to be connected in pairs with a similar pair of message receiving and sending wheels of a signaling apparatus located at 110 each of different substations, a dial having thereon a plurality of sets of messages, an operating handle provided with a pointer and adjustably connected to each of the message sending wheels, a pointer adjustably 115 connected to each of the message receiving wheels, a gong common to all of the message receiving wheels and means actuated by each and all of the message receiving wheels for giving aural signals by the gong. 120

2. A central station signaling apparatus, comprising a plurality of message sending wheels and an equal number of message receiving wheels, a cylindrical casing, a central shaft having bearings centrally arranged in the cylindrical casing and which carries all of the wheels, a shaft at each side of the wheels and parallel to their axis, a pawl for each of the message receiving wheels, a pawl carrying arm on each of the 125 130

side shafts for each of the message receiving wheels, pins or teeth on said wheels for actuating the pawl arms, a single gong, a hammer carried by each side shaft adapted to strike the gong when the side shafts are rocked, an operating handle provided with a pointer and adjustably connected to each of the message sending wheels, a dial having thereon a plurality of sets of messages and a pointer 5 adjustably connected to each of the message receiving wheels.

3. A central station signaling apparatus, comprising a plurality of message sending wheels and an equal number of message receiving wheels, adapted to be connected in pairs with a similar pair of message receiving and sending wheels of a signaling apparatus located at each of different substations, a dial having thereon a plurality of sets of 10 messages, an operating handle provided with a pointer and connected to each of the message sending wheels, a pointer connected to each of the message receiving wheels, a gong common to all of the message receiving 15 wheels and means actuated by each and all of the message receiving wheels for giving aural signals by the gong.

4. A central station signaling apparatus, comprising a plurality of message sending 20 wheels and an equal number of message receiving wheels, adapted to be connected in pairs with a similar pair of message receiving and sending wheels of a signaling apparatus at each of different substations, a cylindrical casing, a central shaft having bearings therein and which carries all of the 25 wheels, a shaft at each side of the wheels and parallel to their axis, a double acting pawl and a carrying arm therefor secured to each 30 of the side shafts and for each of the message receiving wheels, pins or teeth on the sides of said wheels for actuating the pawl arms, a single gong, a hammer carried by

each side shaft adapted to strike the gong when the side shafts are rocked, an operating handle provided with a pointer and connected to each of the message sending wheels, a pointer connected to each of the message receiving wheels and a dial having thereon a plurality of sets of messages. 45 50

5. A central station signaling apparatus, comprising a plurality of message sending wheels, each adapted to be connected to a message receiving wheel of a signaling apparatus located at a distant substation, a dial having a plurality of sets of messages thereon, an operating handle provided with a pointer and connected to each of the message sending wheels, means carried by one of the operating handles whereby it may be 55 connected, at will, to another operating handle, thus causing two substation apparatus to be simultaneously actuated by the operating handle provided with the connecting means.

6. A central station signaling apparatus, comprising a plurality of message sending wheels each adapted to be connected to a message receiving wheel of a signaling apparatus located at a distant substation, a dial having a plurality of sets of messages 60 thereon, an operating lever provided with a handle and a pointer and connected to each of the message wheels, one of said handles being fitted to slide on its lever, and provided with means for connecting it to another handle, whereby two substation apparatus are simultaneously actuated by the operating handle provided with the connecting means. 65 70 75
